UNITED STATES PATENT OFFICE.

WALTER F. GODDARD, OF SOMERVILLE, MASSACHUSETTS, ASSIGNOR TO DUSTLESS VICTORY SIEVE COMPANY, OF BOSTON, MASSACHUSETTS, A CORPORATION OF MASSACHUSETTS.

ASH-SIFTER.

1,344,390.

Specification of Letters Patent. Patented June 22, 1920.

Application filed July 28, 1919. Serial No. 313,841.

To all whom it may concern:

Be it known that I, WALTER F. GODDARD, citizen of the United States, residing at Somerville, in the county of Middlesex, and 5 State of Massachusetts, have invented new and Improved Ash-Sifters, of which the following is a specification.

This invention relates to a new and improved ash sifter and consists in the novel 10 construction and arrangement of parts hereinafter described and claimed.

Referring to the drawings wherein like characters indicate like parts wherever they occur:—

15 Figure 1 is a front elevation of an ash sifter constructed in accordance with my invention, showing the ash sifter in position upon an ash can;

Fig. 2 is a side elevation of the parts 20 shown in Fig. 1;

Fig. 3 is a vertical sectional view on the line 3—3 of Fig. 2, looking in the direction of the arrow, the lower part of the ash can being removed and the parts of the ash 25 sifter being shown on a scale larger than they appear in Fig. 2, in order to illustrate clearly the various parts of the device, there being represented in the ash pan the cinders that have been returned into the ash pan 30 after the sifting operation;

Fig. 4 is a detail perspective view of the screen, ash pan support, and ash pan, the latter being shown separated from its support for the sake of illustrating the parts;

35 Fig. 5 is a vertical sectional view on the line 5—5 of Fig. 1, looking in the direction of the arrow, showing the shaft or spindle upon which the screen-carrier plates are mounted, and also showing the screen and 40 the ash pan and the unscreened ashes and cinders in the pan.

45 1 represents an ash can having a circular top 2. Such structure serves as a support for my improved sifter and as a receptacle for the sifted ashes.

50 My new ash sifter comprises a base or support 3 and a casing 4, see Fig. 5, which carries and houses the operating mechanism or sifting unit. The base 3, as shown, consists of a circular plate provided with a depending flange 6, constructed to be slid down about the top 2 of the ash can, see Fig. 3, permitting the plate or base 3 to rest upon and thus be supported by the top 2. The 55 end wall 4^a of the casing 4, as shown, is

generally circular, except at the bottom where the walls are extended out of the circular plane as at 7, 7, see Fig. 3. The side walls 8, 8^a, consist of plates shaped to correspond to the end wall. The several 60 parts of the casing thus described may be made of sheet metal and secured together in any desired way common in the art.

As shown, the plate 3 is cut away between the ends 7, 7 of the wall 4 and the 65 said plates 8, 8^a, as at 9, see Figs. 3 and 5, to provide a smooth and unbroken passage-way for the ashes from the casing to the can.

An opening is formed near the bottom of the side wall 8^a, or front wall, adapted to 70 be closed by a door 10, see Fig. 1, that is larger than said opening. The door 10 is hinged at its bottom by hinges 11, 11, to the plate 8^a.

A button 12 carried at the top of the door 75 serves to lock the door in place when not unlocked and dropped down to permit the insertion or removal of the ash pan, 13, see Fig. 4.

A shaft or spindle 14 has its ends rotatably mounted in holes in or bearings carried by the side plates 8, 8^a. A crank arm 15 has one end secured upon the projecting end of the spindle 14 outside the plate 8^a, and a handle 16 secured to the other end 85 of said crank arm provides means for turning the spindle or shaft 14 and the parts carried thereby.

17, 17^a represent circular plates mounted upon and secured to the spindle or shaft 14 90 to turn with the latter. The plates 17, 17^a are spaced apart and their lower sides are truncated as at 18, these lines constituting in a general way a chord of their respective circles. The edge 18 in the front plate is further cut away as at 18^a, Fig. 3, to allow the ash pan to be slid under it, see Fig. 5, and against the plate 17. A flat plate 19, see Fig. 4, is secured at one of its sides to the edge 18 95 of the plate 17.

100 Referring to Fig. 3, the left-hand end of the plate 19 is bent up as at 20 while the opposite end is bent up as at 21, the latter being shorter than the former. The plate 19, when the parts are in the position shown in 105 Fig. 3, coincides with the bottom of the opening in the plate 8^a that is closed by the door 10, so that by dropping the door down on its hinges, the ash pan 13 can be slid upon the plate 19, the ends 20, 21 being spaced 110

apart sufficiently to receive the ash pan between them. In this position the ash pan is secured against lateral displacement when the door 10 is closed by the plate 17 on one side and by the plate 8^a, see Fig. 5, on the other.

22 to 30 represent a series of small rods arranged between the plates 17, 17^a, and having their ends secured to said plates. These 10 rods are positioned at increasing distances from the spindle or shaft 14, the rod 22 being the nearest while the rod 30 is the most distant. A strip of wire fabric 31 is arranged between the plates, 17, 17^a mounted 15 upon and secured to the rods 22 to 30, one end of this strip being secured to the rod 22 while the opposite end of the strip is secured to the rod 30. This strip constitutes the screen, the meshes of which are selected 20 to permit the ash to pass through, but to retain the cinders or uncommunited particles.

In operation, the ash pan 13 is taken from the stove, the door 10 of the casing is dropped down, and the pan with its contents 25 slid in place upon the plate 19 between the upturned ends 20, 21. This brings one end of the pan under the rod 22, see Fig. 3, while the other end of the pan is directly beneath the rod 32 whose ends are secured to the 30 plate 17, 17^a. These rods prevent the pan from dropping off the plate 19 toward the spindle 14. The door 10 is then closed and the sifting unit, including the pan and its contents, turned slowly in the direction of 35 the arrow in Fig. 3, by means of the handle 16, in one complete cycle. The position of the pan during this operation can easily be seen by merely turning the drawings. As the pan moves to the left in Fig. 3, in the direction of the arrow, about the spindle 14, the contents of the pan are gradually spilled 40 upon the screen, in the direction of the arrow in Fig. 3, at the end of the ash pan, the ash passing through the screen into the can as indicated by the arrows in Fig. 5. As the pan completes its cycle and during the latter part of its return to the initial position shown in Fig. 3, the cinders and other material retained by the screen 31 runs off 45 the screen over the rod 22 into the pan and can be removed with the latter.

The hole cut in the plate 8^a covered by the door 10, as well as the opening formed by the cut-away portion 18^a of the front plate 50 17^a, are usually about the same size, and are

sufficient to permit the ash pan to pass through said openings when the openings register, that is, when the parts are in the position shown in Fig. 3.

Having thus explained the nature of my 60 invention and described a way of constructing and using the same, though without attempting to set forth all of the forms in which it may be made, or all of the modes of its use, what I claim and desire to secure by 65 Letters Patent is:—

1. An ash sifter comprising a casing and a rotatable unit including two similar heads, means for supporting an ash pan between said heads, and a screen extending from one 70 head to the other with its ends terminating adjacent opposite sides of the pan support and in different horizontal planes, said screen extending about the axis of the unit on a line that gradually approaches said 75 axis from its receiving to its delivery end.

2. An ash sifter comprising a casing, and a rotatable unit including a screen extending about the axis of said unit with its ends situated in different horizontal planes, 80 and means for supporting an ash pan so that the top thereof will be positioned above the plane of the lower end of the screen and the upper end of the screen will extend over one edge of the pan, whereby each rotation 85 of said unit will cause the contents of the pan to be discharged into the screen between the ends thereof and the material retained by the screen will be returned to the pan from the higher end thereof. 90

3. An ash sifter comprising a casing, a rotatable shaft mounted therein, a pair of screen heads arranged on said shaft and secured thereto, means connecting said heads for supporting a wire screen, a wire screen 95 mounted on said means and forming a discontinuous curved wall between the heads, and provisions on said heads for receiving an ash pan at the interrupted part of the screen, one end of the screen being positioned 100 over one end of the ash pan, and the other end thereof being positioned below the opposite end of the ash pan whereby as the parts are rotated the contents of the ash pan will be dumped upon the screen, the ashes 105 passing through the screen and the cinders returned to the ash pan.

In testimony whereof I have affixed my signature.

WALTER F. GODDARD.
